(57) **CLAIM**

The ornamental design for a candle warmer lamp, as shown and described.

DESCRIPTION

FIG. 1 is a first perspective view of a candle warmer lamp showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the candle warmer lamp thereof;

FIG. 10 is a perspective view of another state of the candle warmer lamp thereof; and,

FIG. 11 is an enlarged view of the selected portion 11 in FIG. 1.

The broken lines shown in the drawings depict portions of the candle warmer lamp that form no part of the claimed design.
